CURTAIN SUPPORT FOR AN ARTICLE OF FURNITURE

Joseph A. Muench, New York, N. Y.

Application April 25, 1945, Serial No. 590,289

6 Claims. (Cl. 311—2)

1

This invention relates to an article of furniture having one or more curtains enclosing the space underneath the top thereof, and particularly to an arrangement for slidably supporting the curtains in proximity of the periphery of such top.

Heretofore, dressing tables of the boudoir type have included curtains positioned adjacent the edges of the table tops for enclosing the space therebelow. Known arrangements of fixed and movable types employed for supporting the curtains embodied metallic parts to a great extent. The present invention contemplates a substantially non-metallic support of the slidable non-foldable type for the curtains of a dressing table.

The object is to provide a slidable support for the curtains of a dressing table.

In a specific embodiment, the present invention, disclosed in connection with a curtain-enclosed dressing table, comprises a table top provided with a peripheral groove of pre-selected configuration, and a plurality of discrete elements, each formed in one plane with a configuration complementary to the configuration of the groove for allowing the disposition of the elements in the groove in a slidable manner, the elements being secured in spaced relation to a textile strip which is suitably secured to the curtains. Each element is also formed in a different plane with a configuration which allows expeditious movement of the elements in both rectilinear and curvilinear directions.

The invention will be readily understood from the following description when taken together with the accompanying drawing in which:

Fig. 1 is a plan view of a table top provided with a specific embodiment of the invention;

Fig. 2 is a front elevational view of Fig. 1;

Fig. 3 is a fragmentary enlarged and exploded view illustrating a detachable connection between the curtain and a specific embodiment of the invention;

Fig. 4 is an enlarged cross-sectional view taken along the line 4—4 of Fig. 1;

Figs. 5 and 6 are fragmentary plan views taken along the lines 5—5 and 6—6, respectively, of Fig. 4 at the points A and B, respectively, of Fig. 1;

Fig. 7 is an enlarged cross-sectional view, similar to Fig. 4, of an alternate embodiment of the invention;

Fig. 8 is an enlarged cross-sectional view, similar to Fig. 4, of a further embodiment of the invention, and

2

Fig. 9 is a view taken along the line 9—9 of Fig. 8.

The same reference numerals are employed to designate identical elements appearing in several figures of the drawing.

Referring to Figs. 1 and 2 a table top 10 is supported by a plurality of spaced legs 11 between which are positioned slidable drawers 12, 13 and 14. Depending from the periphery of the table top is a pair of curtains 15 and 16. To facilitate the hanging of these curtains, each has the righthand surface of its uppermost end suitably secured to a first textile band 17, Fig. 3. Spaced in horizontal alignment along the central portion of the righthand surface of the first textile band 17 and suitably fastened thereto, Figs. 1, 2 and 3, is a plurality of elements 18, each of which is formed with a centrally depressed portion 19. As shown in Fig. 3, portion 19 projects through an accommodating opening 20 provided in the first textile band 17, the portions 19 and openings 20 being covered by the respective curtains 15 and 16, as seen from the lefthand side in Fig. 3.

In Fig. 3 a second textile band 21 is held firmly between members 22 and 23 both of which have their central portions formed into a unitary projection 24 to be accommodated in depressed portion 19. These projections are spaced in horizontal alignment along the central portion of the second textile band 21 in such manner as to be disposed substantially oppositely to the depressed portion 19. Thus, the depressed portions 19 and projections 24 constitute complementary members for effectively establishing a detachable connection between the individual curtains 15 and 16 and the table top 10 in a manner that will be presently explained. The foregoing is a familiar structure.

In accordance with the present invention, a specific embodiment includes the periphery of table top 10 in Figs. 1 and 2 provided with a groove 25 of preselected configuration. As shown in Fig. 4, the groove 25 comprises an open side 27 and a side 28 diametrically opposite thereto both of which sides lie in individual vertical planes disposed in parallel relation, and diametrically opposite sides 29 and 30 lying in individual planes each arranged in other than parallel relation relative to the other. A member 35 positioned in the groove 25 in Fig. 4 is formed with a configuration complementary to that of groove 25. Thus, the member 35 embodies two diametrically opposite sides each of which lies in a vertical plane coinciding substantially with

the vertical plane embodying one of the respective sides 27 and 28 of the groove 25, and two further diametrically opposite sides each of which lies in a plane coinciding substantially with the plane embodying one of the respective sides 29 and 30 of the groove 25.

In Figs. 5 and 6 each of a plurality of members 35 includes two diametrically opposite sides 36 and 37 positioned in individual vertical planes each of which is disposed in other than parallel relation with the other. Thus, the members 35 are positioned in the groove 25 for slidable movement in a plane parallel with the horizontal plane of the uppermost surface 26 of the table top 10, Figs. 2, 5 and 6. The members 35 are arranged in two groups each of which has corresponding surfaces suitably secured to one of a pair of second textile strips 21, Fig. 3. A suitable opening 40 located at the rear of the table top 10 in Fig. 1 enables the individual members 35 of each group thereof to be inserted into and removed from the groove 36. As one of the curtains 15 and 16, Fig. 2, is detachably connected to one of the pair of second textile strips 21, each of the respective curtains 15 and 16 can be slidably moved in both clockwise and counter-clockwise directions with reference to a point 41 on the periphery of the table top 10, Fig. 1. In Fig. 5 one group of members 35 is shown disposed on a convex portion of the periphery of the table top 10 such as at the peripheral portion A in Fig. 1; and in Fig. 6 one group of members 35 is shown disposed on a concave portion of the periphery of the table top 10 such as at the peripheral portion B in Fig. 1. Thus, the members 35 slide equally expeditiously in rectilinear and curvilinear portions of the periphery of the table top 10.

In Fig. 7 a groove 45 is provided with a configuration comprising two diametrically opposite sides 46 and 47, of which side 47 lies in a horizontal plane and side 46 is angularly disposed thereto, and an open side 48 and a side 49 diametrically opposite thereto, both of which latter sides are disposed in parallel vertical planes. The side 46 lies at an angle, with reference to the horizontal plane of the table top 10, which is less than a right angle. Positioned in the groove 45 is a member 50 formed with a configuration complementary to that of the groove 45.

In a horizontal plane the member 50 is provided with a wedge-like configuration which is substantially identical with that of the members 35 in Figs. 5 and 6. The member 50 serves the same purpose as the one served by the members 35 mentioned hereinbefore. Thus, a plurality of members 50 may be substituted for the members 35 in Figs. 5 and 6 for supporting the curtains 15 and 16 as hereinbefore described. Obviously, the sides 46 and 47 of the groove 45 in Fig. 7 can be interchanged. This means that the respective sides of the member 50 are also interchanged so that the configurations of the groove 45 and members 50 are complementary to each other.

In Fig. 8 a substantially circular groove 55 supports a substantially spherical member 56 for slidable movement therein. As shown in Fig. 9 a plurality of spherical members 56 is slidably supported in the circular groove 55 for the same purpose as the members 35 in the groove 25, Figs. 4, 5 and 6. In Fig. 8, left-hand surface 57 of the member 56 permits the fastening thereto of the textile strip 21 in a manner similar to that illustrated in Fig. 3. Thus, a plurality of members 56 in Fig. 9 are arranged for slidably supporting the

curtains 15 and 16 in the manner previously explained with reference to Figs. 1 through 6.

The specific forms of the invention described in the foregoing are for the purpose of this illustration, and the invention is not to be limited thereto. It is to be understood that other modifications within the scope of the invention set forth in the appended claims will occur to those skilled in the art. For example, it is obvious that a single curtain can be substituted for the pair of curtains 15 and 16, Fig. 2, within the scope of the invention.

What is claimed is:

1. In combination with an article of furniture including a member and a curtain depending therefrom, said member being formed with a groove having at least two non-parallel opposite sides, and a plurality of elements each having at least two non-parallel opposite sides complementary to said sides of said groove, said elements being accommodated in said groove for slidable movement therein, said curtain being detachably secured to said elements and movable with reference to said member as said elements are slid in said groove.

2. A combination according to claim 1 in which said member is formed with a groove having at least two non-parallel opposite sides of which one side is disposed in parallel relation with reference to an uppermost surface of said member, and the second side is disposed in non-parallel relation with reference to said uppermost surface of said member and said one side.

3. In combination with an article of furniture including a member and a curtain depending therefrom, said member being formed with a peripheral groove having rectilinear and curvilinear sections, said groove in said sections having at least two non-parallel opposite sides, and a plurality of elements each having two opposite sides complementary to said sides of said groove, said elements being accommodated in said groove for slidable movement in said rectilinear and curvilinear sections of said groove, said curtain being detachably secured to said elements and movable with reference to said member as said elements are slid in said rectilinear and curvilinear sections of said groove.

4. In combination with an article of furniture including a member and a curtain depending therefrom, said member being formed with a circumferential groove, said groove having at least two opposite sides each of which is disposed at other than a right angle with reference to a plane of said member, said two sides tending to converge in one direction, a plurality of elements each having at least two opposite sides tending to converge in one direction, said two sides of said elements being complementary to said two sides of said groove for enabling said elements to slide in said groove, said elements being removably attachable to said curtain so that said curtain is moved as said elements are slid in said groove.

5. In combination with an article of furniture including a member having a circumferential edge formed with rectilinear and curvilinear sections, and a curtain depending from said member, said circumferential sections being formed with a groove having a pair of non-parallel sides, a plurality of elements each having two pairs of non-parallel sides tending to converge in opposite directions, one pair of said last-mentioned pairs of sides being complementary to said pair of sides of said groove, said sides of said groove and elements enabling said elements to slide in said

rectilinear and curvilinear sections of said groove, said elements being removably attachable to said curtain, said curtain being moved as said elements are slid in said rectilinear and curvilinear sections of said groove.

6. In combination with an article of furniture including a member and a pair of curtains depending therefrom, said member being formed with a peripheral groove having rectilinear and curvilinear sections, said groove having two non-parallel opposite sides, and a plurality of elements each having two opposite non-parallel sides, said sides of said elements being complementary to said sides of said grooves, said elements being accommodated in said groove and arranged therein in two groups for slidable movement as discrete groups in said rectilinear and curvilinear sections, each of said groups of elements being detachably affixed to one of said curtains, each of said last-mentioned curtains being movable relative to said member as the respective groups of said elements are slid in said rectilinear and curvilinear sections.
